UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,480, dated September 20, 1881.

Application filed August 9, 1881. Term of patent 3½ years.

To all whom it may concern:

Be it known that I, HENRY HUNT, of Greenville, in the county of Hudson and State of New Jersey, have invented a new and original 5 Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The background of the carpet is composed of rows of interlocking oval figures *a a*, so arranged that wherever four ovals overlap in part a fifth they produce within the latter a diamond - shaped central figure, *b*, in which is contained a small cross. On this background is an involved design of many figures, all of

them connected into one system by stems or 20 bars. The most prominent of these figures are the crown-shaped figure A, the rosette B, the fan-shaped figure C, oval figure D, ball-shaped figure E, rosette F, cross-like figure G, leafed rosette H, and angular figure I. 25

I claim—

1. The design for carpets, consisting of the figures A B C D E F G H I and connecting bars, stems, and figures, substantially as shown.

2. The design for carpets, consisting of the 30 figures A B C D E F G H I and connecting stems, bars, and figures, and of the figures *a* and *b*, substantially as shown.

HENRY HUNT.
